UNITED STATES PATENT OFFICE.

FRED C. OLIN, OF BUFFALO, NEW YORK, ASSIGNOR OF ONE-HALF TO DAN-FORTH & CLARK, OF SAME PLACE.

STEAM-PUMP.

SPECIFICATION forming part of Letters Patent No. 415,055, dated November 12, 1889.

Application filed April 11, 1889. Serial No. 306,895. (No model.)

To all whom it may concern:

Be it known that I, FRED C. OLIN, of Buffalo, in the county of Erie and State of New York, have invented certain new and useful 5 Improvements on Steam-Pumps; and I do hereby declare that the following description of my said invention, taken in connection with the accompanying sheets of drawings, forms a full, clear, and exact specification, which will 10 enable others skilled in the art to which it appertains to make and use the same.

This invention has general reference to improvements in steam-pumps; and it consists, essentially, in the novel and peculiar combination of parts and details of construction, as 15 hereinafter first fully set forth and described, and then pointed out in the claims.

In the drawings already mentioned, which serve to illustrate my said invention more 20 fully, Figure 1 is a side elevation of my improved steam-pump. Fig. 2 is a longitudinal sectional elevation of the same, illustrating the parts of the pump at the beginning of the downstroke. Fig. 3 is a similar view of the, 25 same, showing the position of the parts immediately after the beginning of the upstroke.

Like parts are designated by corresponding letters of reference in all the figures.

A in the drawings designates the steam- 30 cylinder of my steam-pump. It is secured to a suitably-constructed base B by means of screws 1, it having flanges on both its ends for this purpose, and for the further object of securing to its upper end the pump-cylinder C. 35 This latter cylinder is smaller than the steam-cylinder, the difference being regulated by the height to which the pump is to lift or the "head" against which it has to force the liquid.

The base B has centrally a cylindrical 40 chamber B', closed on its bottom side by a cap k, said chamber being of two different diameters to produce a shoulder or offset b', for the purpose hereinafter to be referred to. In 45 this base there is, furthermore, a valve-seat against which a flat plate or slide-valve L bears, said chamber B' being in communication with the face of this valve-seat by a steam-port x, while a steam-chest 2 incloses 50 the valve L in a manner readily understood

from the drawings. In the base B, and leading from the cylinder A and through the steam-port x, there is a cylindrical passage fitted with a loosely-fitting plug X, connected with said slide-valve L by a bar 5, said plug 55 X projecting into the steam-cylinder A a suitable distance. In this plug X there is a groove or way 4, acting as a passage between said port x and the steam-cylinder A during a portion of the downstroke of the piston E. 60

Within the chamber B' there is located a valve-piston K, consisting of a central body having on its lower end a rim or ledge 8, fitting the larger portion K' of said chamber B', while its body is smaller than the lesser portion of said chamber, there being near its upper end a projecting ledge or rim 10, to which is screwed a cap-piece k', a series of apertures 9 in said ledge establishing communication between the port x past the central portion of 70 the piston K, and through a series of apertures 6 in said cap-piece k' into the cylinder A.

Below the cap-piece k' just mentioned there is placed a disk-valve 11, which in lifting bears against the under side of the cap-piece k', while normally it is about midway between the rim 10 and the bottom of the cap-piece k'.

Within the steam-cylinder A operates the 80 steam-piston E, while in the pump-cylinder, immediately above, works the pump-piston F, both pistons being connected with one another by a tubular piston-rod T. The steam-piston E has a central passage E', fitted with 85 a valve U, the head of which is below the level of the piston when the valve is closed and even with the bottom of said piston when said valve is open.

The tubular piston-rod T screws with one 90 end into the piston, and it extends with its other end through the water or pump piston into its head 12, there being a stuffing-box 13 in the end of the tubular piston-rod, so as to tightly pack a valve-rod V on that end, and 95 at the same time produce sufficient friction upon said rod to keep it in any position into which it may be put. This rod V projects beyond the head 12 of the pump-piston, and has on its upper end a disk or head v, while 100

its lower end bears upon the valve U, or is attached thereto in any suitable manner.

The pump-piston is hollow, it having a chamber F', from which passages h in the head 12 communicate with the pump-cylinder, while apertures f in the tubular piston-rod opening into the chamber F' establish a communication between the steam and the pump cylinders, which communication is under the control of the valve U, in a manner hereinafter explained.

In the head 12 of the pump-piston there is located a disk-valve F'', (of rubber or other suitable material,) which valve closes the openings h in said piston-head 12 during the upstroke and also during a portion of the downstroke of the said pistons.

On the top of the pump-cylinder, and preferably formed in one piece therewith, is located the valve-chamber D, having suction and discharge valves g' operating upon vertical studs g'', and loosely held upon their seats by coil-springs g''', in the well-known manner, the suction-chamber G' being closed on top by a cap a, and the discharge-chamber G by a bushing b, there being in the latter the discharge-pipe I, while into the chamber G' leads the suction-pipe H.

Through the top wall of the chamber D passes a screw-threaded stop-rod R, having a lock-nut r, said rod being reduced inside of the chamber, at r', to receive a cup s, there being a nut s' on the end of the reduced portion or shank r' to keep said cup upon said shank, a spiral spring S being interposed between the cup s and the shoulder R' to offer a certain resistance to the head v of the rod V when the latter reaches the said cup, and thereby produce an elastic abutment for the same.

Through the lower flange of the pump-cylinder and into the steam-cylinder A projects a lifting-rod N, having on its upper end a laterally-projecting head-piece N', through which passes the valve-rod M, connecting with its lower end with the slide-valve L. On the upper end of this valve-rod is placed a nut d and a washer e, while a spiral spring O is interposed between said washer and the head-piece N', to afford an elastic cushion for the rod N, so that the slide-valve is started easily and without jar when the head of the steam-piston reaches the said rod N.

In the steam-piston E there is a deep annular groove 14, into which is fitted a double-walled shell j j', the outer one of which has a laterally-projecting flange, by means of which and screws i it is fastened to the upper and outer edge of the steam-piston, while the inner one j' terminates in a cone t, the apex of which is soldered or otherwise fastened to the tubular piston-rod T. This double-walled vessel, which, it may here be remarked, is preferably made from sheet metal, leaves an air-space 16 in the annular groove of the steam-piston to act as a non-conductor of heat, to prevent cold water that may pass through the

packing 17 of the pump-piston from coming in contact with the metallic surfaces of the steam-piston and cooling the same, the annular space between the walls j j' serving as a receiver for said water, which is forced out of said annular space every time that the steam-piston reaches the end of the upstroke.

The lining of the pump-cylinder, which is preferably made of brass, projects into the steam-cylinder a certain distance corresponding with the depth of the annular space 18 between the walls j j', so that when the steam-piston approaches the end of the upstroke the projecting end of the lining C', Fig. 3, passing into the annular space 18, displaces the water contained therein and forces it out of the passage 15, leading it to the exterior of the steam-cylinder C, and from whence it may be led by means of pipes (not shown) to any convenient place.

The operation of this pump is substantially as follows: Assume that the steam-cylinder A has been supplied with steam, and that this steam has forced the steam-piston E to the upper end of its cylinder, and that the parts have assumed the position shown in Fig. 2, and that the valve-chamber D was suitably primed, so as to be full of water. Steam passing from the lower side of the steam-piston E through the valve U, tubular piston-rod T, passages f and h into the discharge-chamber G, lifting the disk-valve F'' for this purpose, this steam as soon as it comes in contact with the water in said chamber G is immediately condensed and produces a partial vacuum in said chamber, its passages, the interior of the piston-rod, and the steam-cylinder, so as to immediately start the piston on its downstroke, and water entering the pump-cylinder through the suction-pipe H and valve-chamber G', it being understood that the pistons are forced downward principally by their own weight and by the atmosphere acting upon the steam-piston with a force due to the difference in area between the pump and steam pistons, the space between said pistons being open to the atmosphere through the port 15. When the steam-piston in its downward travel reaches the stop X, it will push it downward and with it the slide-valve L until the latter has opened the port x sufficiently to admit steam to enter the central chamber B' in the base B, said steam passing from the steam-pipe J into the steam-chest 3 in a manner readily comprehended. The current of steam thus passing through the apertures 9 in the rim 10 of this valve-piston K will immediately throw the disk-valve 11 upward against the under side of the head-piece k', and cause the said valve-piston to move outward, meeting the valve U in the steam-piston and closing it while the latter piston is just completing its down-stroke, it being observed that steam passing through a notch 7 in the bottom rim of the valve-piston K, (see Figs. 1 and 2,) below the same, is the medium that forces the said pis-

ton-valve upward. In case the piston E is already so near the end of its downstroke that the valve-piston K cannot rise high enough to disclose the openings 6, Fig. 3, in 5 the head-piece k' above the top surface of the base B, (the bottom of the steam-cylinder,) so as to let steam pass into the steam-cylinder through these openings, the disk-valve 11 will not be in condition to lodge 10 against the under side of said head-piece, and therefore steam will pass through the center opening 19 in said head-piece and force the steam-piston onward on its upstroke, the piston K following it until the 15 openings 6 are above the base B, and thereby a free admission of steam to the steam-cylinder afforded, the exact position of the parts at this point being illustrated in Fig. 3. When the steam-piston E in its downstroke moves 20 the slide-valve L, through the intervention of the push-rod X and the rod 5, the valve-rod M pulls the stop N downward, so that its lower end projects into the steam-cylinder a short distance. As soon as the said piston 25 reaches this stop-rod in its upstroke it will move it upward and thereby pull the slide-valve L shut, the latter taking effect a short time before said steam-piston has completed the upstroke, which is finished by the expansion of the steam in the steam-cylinder. 30 At the point where the slide-valve L has just closed the port x the head v of the valve-rod V in the tubular piston-rod has reached the cup s on the stop-rod R, the 35 exact point being capable of being regulated by screwing the said stop-rod in or out, as the case may be. This will then arrest the upward movement of said rod V, and the pistons, completing the upstroke, will open 40 the valve U to allow the steam in the steam-cylinder to exhaust into the valve-chamber G, and to cause the condensation thereof and the production of a vacuum, (or a partial vacuum,) as already mentioned, and the downstroke of the pistons, the working of the pump 45 being a repetition of the operations of the parts as heretofore set forth. The valve-piston K in the chamber B', after being forced outward by the pressure of the steam, would 50 remain in that position during the downstroke of the steam-piston. To enable it to readily drop back into the chamber B' after the steam-port x has been closed, I form the groove 4 in the rod X to act as a vent, there being also a 55 notch or notches 7 in the rim 8 of said piston for that purpose.

It will readily be observed that, owing to the momentum acquired by the pistons in their up and down strokes, respectively, the 60 action of this pump will be perfectly regular and positive, the number of strokes delivered per minute depending upon the initial steam-pressure as well as upon the head against which the water of the pump is being forced.

65 It will now be further observed that, while this motor operates as either a high-pressure and condensing one, or as a low-pressure and

condensing, the initial steam-pressure being from one to two pounds per square inch upward, yet there is no condenser required to produce the vacuum necessary to produce the downstroke of the pump, all the steam used in the upstroke being condensed by the water lifted by and in contact with the water lifted, and therefore the best results obtained at a 70 comparatively small expenditure of power; all the heat being utilized in raising the temperature of the water raised, so that this pump may readily be used as a boiler-feeder, where it will do as economical service as any injector or other medium condensing the steam used. It may also be used as a tank-pump for railway service, owing to the fact that the temperature of the water pumped will be high enough to dispense with heaters for the same 85 in winter time. In fact, it is well adapted to all the various duties of a steam-pump.

Having thus fully described my invention, I claim as new and desire to secure to me by Letters Patent of the United States— 90

1. In steam-pumps, the combination, with the steam-cylinder and piston, of the base having the central chamber fitted with a piston and disk valve and the steam-chest with its slide-valve, whereby said slide-valve, by allowing steam to act upon the piston in said chamber, controls the admission of steam to said steam-cylinder, as and for the purpose set forth. 95

2. In steam-pumps, the combination, with the steam-cylinder and its piston, of the base having the central chamber, the valve-piston provided with the head, and the disk-valve, and the steam-chest and slide-valve, the latter being actuated by the top and bottom stop-bars, as stated. 100

3. The combination, with the steam-cylinder and its piston, of the base having the central chamber fitted with a piston and valve, said valve being adapted to close against the under side of the head-piece of said piston, as and for the purpose stated. 110

4. The combination, with the base B, having the central chamber B', of the valve-piston K, having the flanged body, the upper rim 115 10, provided with the perforations 9, the disk-valve 11, and the head-piece k', as and for the object specified.

5. The combination, with the base B, having the central chamber B', port x, steam-chest 3, and slide-valve L, of the valve-piston K, consisting of a flanged body having perforations 10, the disk-valve 11, and the head k', with the perforations 6, as and for the purpose set forth. 120

6. In steam-pumps, the combination, with the steam-cylinder and piston, of the base having the central chamber fitted with the piston-valve, the steam-chest with the slide-valve, the push-rod X, connected with said 130 slide-valve by the rod 5, and the push-rod N, having the head N', and valve-rod M, as and for the purpose specified.

7. In steam-pumps, the combination, with

the steam-cylinder, of the piston E, having the central passage E', the valve U, rod V, and the adjustable stop R, as described.

8. The combination, with the steam-cylinder, of the steam-piston and water-piston connected together by a tubular piston-rod, said steam-piston having a valve closing against its bottom and the pump-piston having a valve closing upon its top surface, as and for the purpose set forth.

9. The combination, with the steam-cylinder and pump-cylinder, of the steam and pump pistons connected together by a tubular rod, as described, said steam-piston having the valve U and rod V, and the pump-piston provided with the chamber F', passages f and h, and the valve F'', the valve U, rod V, and the pump-piston having the chamber F', passages f and h, and the valve F'', the valve U in said steam-piston being closed and opened by movable stops, as and for the object stated.

10. The combination, with the steam and water pistons, of a valve located in said steam-piston, adapted to open and close communication between the steam and pump cylinders, passages between the steam and water cylinders, and valves in the valve-chambers, whereby the exhaust of the steam-cylinder is discharged into the water in the valve-chamber, as and for the purpose set forth.

11. In steam-pumps, the combination, with the steam and water cylinders, of connected pistons for both cylinders, a slide-valve governing the admission of steam to a central chamber in the base, a piston-valve in said chamber, a check-valve on the lower end of the tubular piston-rod, and a disk-valve on the upper end of the pistons, and stops for opening and closing said valves, as and for the purpose set forth.

12. In steam-pumps, the combination, with the steam-piston, of the double-walled non-conductor affixed to and entering the annular groove in said steam-piston, as and for the object stated.

13. In steam-pumps, the adjustable stop R, having the shank r', cup s, and spiral spring S, in combination with the piston, the valve U, and rod V, as stated.

14. The combination, with the steam-piston, of the tubular piston-rod, the water-piston having the chamber F', head 12, with the passages h, and the disk-valve F'', as stated.

In testimony that I claim the foregoing as my invention I have hereto set my hand in the presence of two subscribing witnesses.

FRED C. OLIN.
